UNITED STATES PATENT OFFICE.

CHARLES C. HANSEN, OF EASTON, PENNSYLVANIA, ASSIGNOR TO INGERSOLL-RAND COMPANY, OF JERSEY CITY, NEW JERSEY, A CORPORATION OF NEW JERSEY.

CUSHION HANDLE.

Application filed December 1, 1925. Serial No. 72,542.

This invention relates to rock drills, but more particularly to a cushion handle for that type of rock drill which is supported and guided by the operator.

One object of the invention is to prevent the transmission of excessive shocks and vibration to the guiding handle of the rock drill.

Other objects will be in part obvious and 10 in part pointed out hereinafter.

The invention consists of the combinations of elements, features of construction and arrangement of parts having the general mode of operation substantially as hereinafter 15 described and more particularly pointed out in the appended claims and illustrated in the accompanying drawings, in which—

Figure 1 is a side view in elevation partly in section of a portion of a rock drill 20 equipped with a cushion handle constructed in accordance with the practice of the invention,

Figure 2 is a top plan view of Figure 1 partly in section, and

Figure 3 is a perspective view of the 25 resilient supports.

Referring to the drawings, the invention is shown embodied in a hand held type rock drill in which a back head A, a cylinder B, 30 a front cylinder washer C and a front head D are held in operative position by means of side bolts E. The side bolts E are arranged on opposite sides of the rock drill and preferably exterior thereof to engage various 35 lugged portions of the parts comprising the drill casing, such as the back head, the cylinder and the front head, for holding said casing parts against relative rotation.

Pressure fluid may be supplied to the rock 40 drill through a suitable connection F and its admission to the rock drill is controlled by a suitable throttle valve (not shown) having a controlling lever G. Secured to the cylinder B as by means of screws H is 45 a valve chest J wherein may be arranged a suitable valve (not shown) for distributing the pressure fluid to the cylinder B. In this instance a back head plug K is shown 50 screwed in the rearward end of the back head A for holding in a well known manner a cleansing fluid conducting tube (not shown).

In accordance with the present invention, 55 a pair of supports designated generally by L are in this instance formed of single

pieces of wire and are provided with loops O having apertures P for the reception of the side bolts E. The supports L in this instance have straight portions Q which are adapted to seat on the back head A and 60 have off-set curved resilient portions R which terminate at their free ends in loops S. Apertures T formed by the loops S are adapted to receive a bolt U comprising a part of a handle V whereby the rock drill 65 may be manipulated. The bolt U may be of a length to extend well on either side of the supports L so that grip portions W, preferably of rubber, may be arranged slidably thereon. A similar grip portion X is in 70 this instance arranged on the bolt U between the supports L and serves as a spacer for holding the curved portions R of the supports L against relative movement on the bolt U. 75

In order to provide flat surfaces for the ends of the sleeves W and the spacer X adjacent the loops S of the supports L, suitable washers Y are arranged on the bolt U. The washers Y in this instance are cupped 80 as at Z to conform to the shape of the loops S and have recesses b to cooperate with the curved portions R of the supports L for holding said washers against rotation. One end of the bolt U is in this instance screw 85 threaded as at c to receive a suitable nut d whereby the parts comprising the handle may be firmly clamped in position.

Suitable means are provided for preventing rotation of the side bolts E. To this end washers e are arranged between the loops O of the supports L and heads f of the side bolts E. The washers e are provided with upwardly extending projections g having flat sides h which in this instance cooperate 90 with flat faces i formed on the heads f of the said bolts E. The washers e like the washers Y are also cupped as at Z to receive the loops O and are provided with recesses b into which one side of the straight 100 portions Q may extend for preventing relative rotation between the supports L and the washers e.

Although the supports L are in this instance shown as being formed of single 105 pieces of wire and then bent in the manner hereinbefore described for supporting the handle W yieldably with respect to the rock drill, it is to be understood that said supports may be formed of flat stock if de- 110

sired, or of any other suitable material possessing the property of resiliency.

This invention has been found to function in an unusually efficient manner. The transmission of shocks and vibration from the drill to the operator will be greatly minimized, and in consequence the drilling efficiency of a tool thus equipped will be considerably increased.

10 By arranging the handle W in a plane off-set from the longitudinal axis of the rock drill, ready access for adjustment and inspection may at all times be had to the back head plug K and its associated parts.

15 I claim:—

1. In a cushioning device for rock drills, the combination of a back head, a handle for the back head, resilient supports mounted on opposite sides of the back head to yieldably support the handle in a plane off-set from the longitudinal axis of the back head, said resilient supports having straight portions to seat on the back head and curved resilient portions, loops at the 20 ends of the curved portions for the insertion of the handle, and side bolts inserted through the ends of the straight portions for securing the resilient supports to the back head.

2. In a cushioning device for rock drills, the combination of a back head, a handle for the back head, resilient supports

mounted on opposite sides of the back head to yieldably support the handle in a plane off-set from the longitudinal axis of the 35 back head, said resilient supports having straight portions to seat on the back head and curved resilient portions, loops at the ends of the curved portions for the insertion of the handle, side bolts inserted 40 through the ends of the straight portions for securing the resilient supports to the back head, and means for preventing relative rotative movement between the resilient supports and the side bolts. 45

3. In a cushioning device for rock drills, the combination of a back head, a handle for the back head, supports mounted on opposite sides of the back head to yieldably hold the handle, said resilient supports having straight portions to seat on the back head and off-set resilient curved portions, 50 loops formed on the ends of the curved portions for the reception of the handle, side bolts inserted through the ends of the straight portions for securing the supports to the back head and washers cooperating 55 with the side bolts and the supports for holding said supports and the side bolts against relative rotative movement. 60

In testimony whereof I have signed this specification.

CHARLES C. HANSEN.
